APPARATUS FOR EXHIBITING DIVERSE ARTICLES

Enrique Jacobo Marchand, Buenos Aires,
ArgentinaApplication January 4, 1950, Serial No. 136,693
In Argentina September 26, 1949

4 Claims. (Cl. 211—1.6)

1

The present invention relates to an apparatus for successively exhibiting diverse articles from a relatively concealed storage area to an exhibiting area, and has for its object the provision of a plurality of slidably mounted article-supporting members and a carrier sweeping over and beyond the zone of the article-supporting members to pick them up in individual succession and turn them about in exhibiting area so that they may be viewed by a prospective customer.

Another object is the provision of an apparatus of the type described providing a relatively simple and practical construction for carrying out article display.

Other objects will appear as the description proceeds.

In the drawing:

Figure 1 is a top plan view of a preferred embodiment of the invention.

Figure 2 is a partial vertical sectional elevation looking in the direction of the arrows 2—2 of Figure 1.

Figure 3 is an enlarged detail sectional view of approximately one-half of the construction shown in Figure 2 but with the parts on the left hand side of Figure 2 in the position they appear at the right hand side thereof.

Figure 4 is a detail plan view partly in section of the optional latch means for preventing undesired turning of an article being exhibited.

Figure 5 is a detail vertical section of a portion of the chain and the article pick-up means, the hook of the pick-up means being shown in its inoperative position by dotted lines and in its operative position in full lines.

Figure 6 is an enlarged detail sectional view showing an article supporting member in relation to the pick-up means, the latter being shown disengaged from the cross head of the article supporting member.

Similar references designate corresponding parts in the several figures.

In the drawing, F denotes a box-like frame surmounting a lower cabinet portion, not shown. A motor 1 is mounted in the lower part of the frame and drives a speed reducing mechanism 2 which in turn operates a hollow shaft 3 containing an upwardly extending carrier driving shaft 3a.

At this point it may be noted that the frame F and its cabinet portion is preferably of semi-circular shape in horizontal cross-section so that the arcuate rear portion may be conventionally termed a storage area and the diametral side between the corners A and B may be termed the exhibiting area.

2

The parts 3a of the shaft extending above the top wall 4 is rotatable in a bushing 5 and its upper end has rigidly affixed thereto an arched bracket 6 from the opposite ends of which are suspended a carrier C including a pair of arms 7a and 7b extending in opposite directions from the shaft for a total length substantially equaling the diameter of the arcuate top wall 4. The enlarged center portion C' of the carrier C is supported from below by a series of roller bearings 8 carried by the upper ends of posts 8a mounted on a base plate 8b which supports the bushing 5.

An endless chain 9 is suitably guided around the arcuate wall of the frame or cabinet and also extends diametrically across the front of the top wall 4 due to the opposite sprockets 10 and 10' mounted on the underside of the said top wall for adjacent corners A and B.

A sprocket wheel 11 rigid with the tubular shaft 3 and below top 4 has a driving engagement with the substantially straight portion of the chain between the sprockets 10 and 10'. The chain 9 carries a plurality of spaced pusher abutments 12 which engage with and propel article supporting members 13, each of which is provided with a notch 13' on its underside to freely slide on the outer edge of a U-shaped track or rail 14 attached to the semi-circular part of the frame.

Each of the article supporting members 13 which suspend the particular article to be exhibited carries a vertically disposed article suspending bar 15 whose lower end may be provided with any desired type of supporting member, such as eye, hook or hanger. The article suspending bar 15 includes an upwardly projecting stem 16 provided with a cross head 17 adapted to be selectively engaged by pick-up and rotating means at the outer end of each arm 7a and 7b. The pick-up means is constituted by the bifurcated curved end 18 of a hook 19.

The upper end of each hook 19 is swingably mounted on a horizontal pivot 20 supported between the vertical legs 21 of an inverted U-shaped suspending bracket 21a. A pair of coil springs 22 are fitted about the portion of the spindle 20 between each leg 21 of the bracket and the hook 19, and each spring terminates in a part pressing against the hook normally to urge the same to an inoperative horizontal position shown in dotted lines in Figure 5 and in operative position in full lines at the left hand side of Figure 3 and the right hand side of Figure 2.

Each bracket 21a is carried by a tubular sleeve 21a for rotation in a bushing 23 fixed in the end of each arm 7a and 7b. The upper end of each sleeve carries a bevel pinion 24 meshing with

bevel pinion 25 rigid with horizontal shaft 26 above and parallel to its related arm and having gear 38 later to be described. The purpose of this rotation of the sleeve is to turn the article to be exhibited in front of the diametral side of the frame while suspended from one of the moving arms 7a or 7b.

A thrust rod or plunger 27 is slidably mounted in the tubular stem 21b and its upper angular end 21a (Figures 3 and 5) is connected to the slotted end of link 28 fulcrumed at 28a on the upper end of standard 28b rising from an arm of the carrier C. The other end of link 28 is pivotally connected to one end of link 29 whose opposite end is also pivoted to horizontal bar 30 medially slotted to be guided by 30a on the arm 7a, the end of link 30 opposite link 29 is pivotally connected to the lower end of the shank 31' of a T-shaped rocker 31 symmetrically fulcrumed at its midpoint of its head to a standard S mounted on its related arm 7a.

The ends of the head of the T-shaped rocker are pivotally connected respectively to cam rods 32 and 33. The shank 31' of the T-shaped rocker is connected to one end of the spring 35 whose other end is attached to cam rod 32 extending through hole 32a in arm 7a. The cam rod 32 is provided on its side facing the rocker, a notch 32' said notch being adapted to receive an edge of said hole when the cam rod 32 is depressed as shown in Figure 3. The cam rod 32 becomes disengaged from the edge of the hole when the lower end thereof engages cam 37' as will later appear.

Cam rod 33 extends through a bushing 33a and is encircled by spring 35' reacting against the bushing and urging the lower end of rod 33 equipped with roller 33' to a predetermined lower position with respect to top wall 4 carrying elevating ramp 37. The upper edge of this ramp is inclined upwardly for lifting cam 33 as arm 7a, for example, moves to rock 31 and cause rod 32 to be locked in its lower position.

The kick-out cam 37' is fixed to the top wall 4 on the side of shaft 3 opposite ramp 37 and is curved on its side so as to shift cam rod 32 laterally to one side to release notch 32' from the side of the hole in the arm to cause spring 35' to restore the rod 32 to normal upper position.

The inner end of shaft 26 carries a pinion 38 meshing with pinion 39 fixed to a vertical shaft 40 having its lower end journaled in the carrier C. A planetary Geneva gear wheel 41, Figure 2, is splined to the lower end portion of shaft 40 and has a plurality of radial recesses, Figure 4, each adapted to receive a series of teeth 42 of a fragmentary gear 43 fixed to bushing 5 by fastening 43a to turn wheel 41 and also impart motion to shafts 40 and 26, the sleeve 21b, and bracket 21a.

To hold the Geneva gear wheel 41 stationary when there are no teeth 42 on wheel 43 in engagement therewith, a cam disk 44 and a detent member 45 are provided. Said member is moved forward by spring 45a to cause tip of finger 45' to enter a tooth valley on the wheel, while tip of finger 45'' rides on normal periphery of cam disk 44. Said cam disk 44 has cam projections 46 and 47 whose outer periphery corresponds to the number of teeth 42 on gear 43. Thus, when tip of finger 45'' is on the dwell of projections 46 and 47, the latch end of finger 45 is disengaged from the valley of the tooth of the Geneva wheel 41 so that the latter is free to turn under the influence of the teeth 42 on gear 43. Therefore, cam disk 44

will keep the suspended article from turning or rotating, if not desired, while on display.

Operation

Assuming that the carrier C is rotating in the direction of the arrows in Figure 1, it will be seen that the arms 7a and 7b thereof each carrying pick-up means for the article suspending members sweep successively over the arcuate track 14 and across the exhibiting area.

When the arm member 7a is turning in the direction of the arrow in Figure 1 and article supporting member 13 has been picked up by its related hook 19 the said article supporting member 13 will be free from the track 14 and convey the article suspending member and the article itself from point A toward point B and eventually replace the pick-up carrier member back on the track 14.

As previously explained, Figure 3 is the enlarged view of the parts shown at the right hand side of Figure 2 where the hook 19 has engaged the cross-head 17 of an article supporting member. This action takes place by reason of the fact that cam rod 33 has moved to the top of ramp 37 thereby to be elevated and rocking T-shaped lever 31 counter-clockwise, moving linkage 30, 29, 28, to depress plunger 27 to cause hook 19 to engage cross-head 18 as member 13 is about to leave the chain.

As end x of arm 7a leaves corner or point A, the article supporting member 13 is rotated because hook 19 is mounted on spindle 26 of bracket 21 which is integral with sleeve 23 and turned by gears 24-25 to enable the article moving between points A and B to have all sides exhibited to a viewer. During this period the chain 9 moves diametrically and has no effect on the member 13 which is carrying the exhibited article.

When the end x of arm 7 approaches corner or point B to end the exhibition period it puts the member 13 back on track 14 substantially at said point B and the moving chain 9 has one of its pusher elements 12 engage the said member 13 and begins to push it along the track.

Shortly after the article supporting member 13, which has completed its exhibition cycle, is on the track 14 and the arm 7a continues to turn, and the hook 19 is released from cross-head 17. This occurs when arm 7a passes over the kick-out cam 37' and pushes the lower end of cam rod 32 to one side and thus disengages notch 32' from the edge of hole 7 and permits spring 35'' to release its energy to push cam rod 33 down, move T-shaped lever 31 clockwise and cause linkage 30, 29, 28, to lift plunger 27 and enable hook 19 to return to its horizontal position, shown in full lines in Figures 2 and 6 and dotted lines in Figure 5, under the influence of its springs 22, Figure 6.

Therefore, the member 13 which has completed its exhibition cycle is then pushed along the track 14 by its related pusher 12. Meanwhile arm 7b moving in advance of arm 7a, upon approaching point A has its related hook 19 made ready to pick up another member 13 due to ramp 37 actuating the linkage and plunger of the corresponding hook.

When the arms 7a and 7b turn continuously as the motor operates the related hook 19 at the outer end will continue to pick up a related member 13 at point A and carry it on its exhibition cycle and then return it to the track at point B.

I claim:

1. A display apparatus, including, a cabinet-like support having a top wall, an arcuate wall,

a substantially diametrically disposed wall, a track supported on and conforming to said arcuate wall and terminating at the junction therewith of said diametrically disposed wall, a chain mounted to follow a path conforming to said track and said diametrically disposed wall, a carrier having opposite diametrically disposed arms, a motor driven shaft supporting the carrier, means on the shaft for driving the chain and carrier simultaneously, a plurality of article supports slidable on the track, impeller elements on the chain at spaced intervals for pushing the article supports along the track, pick-up means carried by the end of each arm for selectively engaging article support and removing it from the track whereby it may be displayed in front of said diametrically disposed wall, ramp actuated link and lever means for rendering said pick-up means operative and inoperative, and shaft and gear means for rotating said article support while suspended from said pick-up means.

2. A display apparatus according to claim 1, wherein, the article supports include a cross-head and the pick-up means includes a hook normally spring biased to inoperative position and actuated to engage the cross-head by said ramp actuated link and lever means.

3. A display apparatus according to claim 1, wherein, the article supports include a cross-head and the pick-up means includes a hook spring biased to normally disengaged position relative to the cross-head, a rotatable bracket carrying the hook and actuated by said shaft and gear means, and a plunger rod for forcing the hook to engage the cross-head actuated by said ramp actuated link and lever means.

4. A display apparatus according to claim 1, wherein, the pick-up means includes a hook spring urged in one direction, and said ramp

actuated link and lever means includes a plunger rod for forcing the hook in position to engage a related portion on an article support, a horizontally pivoted link engaging the upper end of said rod, a T-shaped rocker mounted on an arm of the carrier, other link means connecting the lower end of the shank of the rocker with the end of said horizontally pivoted link opposite the plunger, cam rods pivotally suspended from the outer ends of the head of the T-shaped rocker and projecting through openings in a related arm toward the said top wall, one of said rods having a lateral notch and the other of said rods being spring depressed, a spring connecting the shank of the T-shaped rocker and the rod having the notch to pull the rod in position to cause said notch to engage with the side of the hole, an elevating ramp on the top wall to elevate the spring depressed rod and automatically cause the notch in the other rod to engage the side of the hole, and a kick-out cam on the top wall at the side of the shaft opposite the elevating ramp to shift the rod with the notch out of engagement with said hole.

ENRIQUE JACOBO MARCHAND.
